PAPER AND TRASH PICKER TONGS AND
THE LIKE

William H. Moore, Los Angeles, Calif.

Application June 9, 1939, Serial No. 278,375

2 Claims. (Cl. 294—19)

This invention relates to certain new and useful improvements in paper and trash picker tongs and the like.

The primary object of the invention is to provide paper and trash picker tongs and the like, especially designed for use by custodians and janitors of school houses, school yards, public parks and buildings, hotels and is especially serviceable for picking up articles in and behind shrubbery, hedges, radiators and the like.

A further object of the invention is to provide a device of the foregoing character in the form of a pair of tongs having relatively wide gripping jaws with the two jaws mounted upon a common pivot at the outer end of the rod or handle of the desired length, the gripping jaws being in a normal open position and adapted to be simultaneously and manually moved to closing or gripping position at their pivotal mounting at the outer end of the handle.

With the above and other objects in view that will become apparent as the nature of the invention is better understood, the same consists in the novel form, combination and arrangement of parts hereinafter more fully described, shown in the accompanying drawing and claimed.

In the drawing:

Figure 1 is a side perspective view, partly broken away and shown in section of paper and trash picker tongs and the like constructed in accordance with the present invention, showing the gripping jaws in their normally opened position;

Figure 2 is a fragmentary side elevational view showing the gripping jaws in their partially closed position;

Figure 3 is a cross-sectional view taken on line 3—3 of Figure 2; and

Figure 4 is a cross-sectional view taken on line 4—4 of Figure 2.

The paper and trash picker tongs and the like comprises an elongated handle rod of the desired length for the character of invention disclosed, with a hand grip 6 at its inner end, while the outer end of the handle rod 5 carries a pair of cooperating gripping jaws pivotally attached thereto. For clarity of description, the two pivotally mounted gripping jaws will be referred to as upper and lower jaws and said upper and lower jaws are respectively designated in general by the reference characters 7 and 8. The gripping jaws 7 and 8 are preferably formed of sheet metal, the lower jaw 8 comprising a comparatively wide plate 9 that is substantially flat or straight at its outer end and gradually increas-

ing in dished formation towards its inner end, the dished formation providing a pair of diametrically opposite parallel ears 10 pivotally supported upon a pin 11 extending transversely of the forward end of the handle rod 5. The lower jaw 8 inwardly of the pivot pin 11 is of substantially U-shape in cross-section as shown at 12 and the inner end of said jaw at the U-shape portion carries a pair of laterally directed arms 13 disposed at opposite sides of the handle rod 5 with the terminal ends of the arms 13 reduced and directed toward each other as at 14 for purposes presently to appear.

The upper gripping jaw 7 has a jaw plate 15 of the general formation of the lower gripping jaw 8 and the inner end of the jaw plate 15 carries a pair of laterally directed arms 16 that overlie the pivot ears 10 of the lower jaw 8 as shown in the drawing with the terminal ends of the arms 16 reduced and directed toward each other as shown at 17 beneath the lower jaw 8 for purposes presently to appear, the arms 9 being mounted upon the pivot pin 11 that pivotally supports the lower jaw 8. The jaw plates 9 and 15 are reinforced by longitudinally extending ribs.

The operating means for moving the gripping jaws 7 and 8 upon their common pivot pin 11 comprise an elongated rod 18 extending longitudinally of the handle rod 5, the forward end of the rod 18 having a pivot pin connected 19 with the reduced terminal ends 17 of the side arms 16 of the upper jaw 7 beneath the lower jaw 8. As shown more clearly in Figure 1, the handle rod 5 is longitudinally slotted as at 20 and a clamp 21 carried by the rod 18 below the handle rod 5 extends upwardly into said slot 20 and has pivotally attached to its upper end as at 22, one end of a connecting rod 23 while the other end of said connecting rod 23 is pivotally attached as at 24 to the reduced ends 14 of the upstanding arm 13 of the lower gripping jaw 8. The inner end of the rod 18 is attached as at 25 to the hand lever 26 that is pivotally attached as at 27 to the hand grip 6 at the inner end of the handle rod 5. An eye-bolt 28 or the like projects laterally of the handle rod 5 at a point inwardly of the gripping jaws 7 and 8 through which the rod 18 extends, the eye-bolt 28 forming an abutment for one end of a coil spring 29 enclosing the rod 18 between said eye-bolt 28 and clamp 21, the spring 29 being operative for forwardly projecting the clamp 21 which moves the clamping jaws 7 and 8 to an open position on their pivot pin 11.

From the above detailed description of the de-

55

vice, it is believed that the construction and operation thereof will be at once apparent, it being noted that the gripping jaws 7 and 8 are normally in an open position and upon operating the hand lever 26, the rod 18 and clamp 21 are retracted against the tension of the spring 29 for moving the gripping jaws 7 and 8 on their pivotal connection 11 to a closed gripping position as suggested in Figure 2 of the drawing. To facilitate carrying of the device, the handle rod 5 is provided with a spring clip 30 by which the device may be attached to the belt or waist-line of the person using the same or to a trash receptacle being carried.

While there is herein shown and described the preferred embodiment of the invention, it is nevertheless to be understood that minor changes may be made therein without departing from the spirit and scope of the invention as claimed.

20 I claim:

1. Tongs of the character described, including a handle rod, a pair of gripping jaws pivotally mounted on a pin at the outer end of the handle rod, each jaw having a pair of arms extending to the opposite side of the handle rod, operating means for the jaws including a hand lever at the inner end of the handle rod, a slide rod adjacent and parallel with the handle rod connected at its inner end to said hand lever and pivotally con-

nected at its outer end to a pair of arms of one jaw, an eye-bolt carried by the handle rod through which said slide rod extends, a link connection between the slide rod and the pair of arms carried by the other jaw and a coil spring 5 on the slide rod between the eye-bolt and link connection for tensioning the slide rod and normally holding the gripping jaws in open position.

2. Tongs of the character described, including a handle rod, a pair of gripping jaws pivotally mounted on a pin at the outer end of the handle rod, each jaw having a pair of arms extending to the opposite side of the handle rod, operating means for the jaws including a hand lever at the inner end of the handle rod, a slide rod adjacent 10 and parallel with the handle rod connected at its inner end to said hand lever and pivotally connected at its outer end to a pair of arms of one jaw, an eye-bolt carried by the handle rod through which said slide rod extends, an abutment 15 on the slide rod, said handle rod having a slotted opening therein in which said abutment is slidable, a link connection between said abutment and the pair of arms of the other jaw and a coil spring 25 on the slide rod between the eye-bolt and abutment for tensioning the slide rod and normally holding the gripping jaws in open position.

WILLIAM H. MOORE.
